(57) CLAIM

The ornamental design for adjustable pool bridge, as shown and described.

DESCRIPTION

FIG. 1 is a front perspective view of the new adjustable pool bridge of this design, wth the angular adjustment set at the midpoint.

FIG. 2 is a top rear perspective view with the top angular adjustment rotated to the right. The stick shown in dashed lines and used therewith forms no part of this design.

FIG. 3 is a view similar to FIG. 2 with the angle adjustable rotated to the left.

FIG. 4 is a bottom plan view of the device of this design with the angle adjustment set at midpoint.

FIG. 5 is a rear elevational view of the device of this design.

FIG. 6 is a front elevational view of the adjustable bridge of this design.

FIG. 7 is a top plan view of the device of this design.

FIG. 8 is a left side view of the device of this design; and, FIG. 9 is a right side view of the device of this design.

FIGS. 4,7,8 and 9 are all depicted as taken from a point of view wherein the assumption is made that the angle adjuster is in the middle portion location as in FIG. 5.
